UNITED STATES PATENT OFFICE

2,416,142

ADJUSTABLE LINED CONTAINER HAVING
INTERCHANGEABLE SCREW-THREADED
SECTIONS

Thomas F. Bennett, Joplin, Mo., assignor to
Hercules Powder Company, Wilmington, Del.,
a corporation of Delaware

Application January 26, 1943, Serial No. 473,607

5 Claims. (Cl. 220—4)

1

This invention relates to an improved container and more particularly to an improved container having means adapted to permit variation of the cubic content thereof.

In general, containers are provided for the purpose of receiving an article in protecting relationship therewith and for the purpose of facilitating handling thereof. Where the article to be handled and protected is of a fixed volume, the container likewise may have a fixed cubic content. However, where the volume of the article is not fixed, it is necessary, in order to handle and protect the article in the most efficient and economical manner, to provide containers of various cubic content. Again, where it is not possible to foresee within what limits of volume the article will take, it becomes extremely difficult to provide a sufficient cubic content range of containers. Consequently, there are times when a proper container is not immediately available for efficiently and economically protecting and handling the article.

Therefore, the object of the present invention is to provide a single container designed to efficiently and economically protect and facilitate handling of articles regardless of their volume size.

Another object is to provide a container made up of adjustable units constructed and arranged in such a way as to permit cubic content variation of the container.

A further object is to provide container inserts comprising tubular units threadedly interconnected and movable relative to each other in such a manner as to permit variation in the cubic content of the inserts and permit interconnection of the insert with additional inserts.

Generally described, the present invention comprises a tubular container made up of a plurality of adjustable inserts or container units. The container units consist of a liner provided with a peripheral thread, and a sleeve of substantially the same length as the liner and adapted to be received on the liner in thread interlocking relationship. A container of any desired cubic content may be made up by assembling the desired number of units into one continuous container unit. The assembly is performed by first partly disengaging the liner and sleeve of each unit, thereby providing a connecting means at each end of the partly disengaged unit. Corresponding connecting means are then interconnected with each other to form a single continuous container. Suitable cap units are provided for closing the open ends of the container.

2

Having now indicated in a general way the nature and purpose of this invention, there follows a more detailed description of preferred embodiments thereof with reference to the accompanying drawing in which:

Fig. 1 is a plan view, partly in section, showing an improved container including one type of closure units.

Fig. 2 is a plan view of the improved container including another type of closure unit.

Fig. 3 is a plan view of the improved container including both types of closure units.

Fig. 4 is a view in cross section of one type of closure cap.

Fig. 5 is a plan view partly in section showing the liner fully disengaged from the sleeve.

Fig. 6 is a plan view partly in section showing the sleeve fully disengaged from the liner.

Fig. 7 is a plan view of another type of closure cap.

The containers shown in Figs. 1, 2, and 3 are made up of one or more container units or inserts indicated generally at 10. The component parts of the container unit 10 are clearly shown by Figs. 5 and 6. Figs. 1, 2, and 3 also show various arrangements of the container inserts 10 and the caps shown in Figs. 4 and 7. Each container unit comprises an inner sleeve or liner 11 shown in Fig. 5 and an outer sleeve 12 shown in Fig. 6.

30 The liner 11 may be made of any suitable tubular material as, for example, wood, metal, synthetic material, or paper. The liner 11 is provided with a spiral spaced thread forming band 13 mounted on the peripheral surface thereof as clearly shown in Fig. 5. The upstanding thread 13 on the sleeve 11 may be formed by applying spirally any suitable thread forming means as, for example, a cord 14 on the surface of the liner extending from one end to the other. The cord 14 may be held in place in any suitable manner as

35 by means of the overlaid band of paper 15 which is relatively thin and which is secured to the cord 14 and the surface of the sleeve by any suitable adhesive. A more detailed disclosure 40 for forming this cord type thread may be found in the application to Latimer and Smith, Serial Number 455,756, filed August 22, 1942, now Patent No. 2,405,909.

The sleeve 12 may be made of any suitable tubular material as, for example, wood, metal, synthetic material, or paper. The inner surface of the sleeve 12 is provided with a spiral spaced thread receiving groove 16. When the sleeve 12 is made up of a number of plies or strips of 45 paper 17 and 18, the thread receiving groove 16

may be formed by spacing the strip 18 as it is being fed to a mandrel (not shown) so as to provide the groove 16, the width of which is dependent upon the spaced relationship between the opposing sides of the strip 18. Proper arrangement of additional plies 17 with respect to the ply 18 in accordance with methods well known in the art complete the construction of the sleeve 12. The pitch of the thread receiving groove 16 and the pitch of the upstanding thread 13 are of an equal value in order that the sleeve may be received upon the liner in thread interlocking relationship. A more detailed disclosure for forming this thread receiving groove may be found in the above noted application.

Fig. 4 shows a female type container closure 19 which may be made of any suitable material as, for example, wood, metal, synthetic material, or paper. Where the cap is made of plies of paper in a manner similar to that described with reference to the sleeve 12 a thread receiving groove 16 is provided on the inner surface of the cap 19 in a manner very similar to that described with reference to the sleeve 12. The cap 19 is similar generally in construction to the sleeve 12 except that the cap is closed at one end in any well known manner and further that the thread receiving groove 16 extends inwardly of the cap substantially half-way of the overall length of the cap and terminates at the shoulders 20. The pitch of the thread receiving groove 16 of the cap 19 is of the same value as the pitch of the thread 13 on the sleeve 11 so that the sleeve 11 may be received in thread interlocking relationship with the cap 19.

Fig. 7 shows a male type container closure cap 21 which may be constructed of wood, metal, synthetic material, or paper. The threaded portion of the cap is constructed in a manner similar to the manner in which the liner 11 is constructed. The threads 13 terminate at the shoulder portion 22 of the cap 21 and are of the same pitch value as the thread 13 on the liner 11, so that the sleeve 12 may be received in thread interlocking relationship with the threaded portion of the cap 21. Both ends of the tubular cap 21 are closed as shown at 23 and 24 in any suitable manner.

From the foregoing disclosure, it may be readily appreciated that the liner 11 and sleeve 12 used either alone or in conjunction with other liners and sleeves and in conjunction with the caps 19 and 21 may be interconnected to form a container, the cubic content of which is dependent upon the number of units used in making up the container. Thus, Fig. 2 shows a container made up of three sleeves 12 held in interlocked relationship with each other by means of the two liners 11, and closed at each end by the container closure cap 21. Another arrangement of parts is shown by Fig. 3, wherein one sleeve 12 and one liner 11 are moved to partly engaged relationship with each other and the sleeve end of the unit is closed by the cap 21 and the liner end of the unit is closed by the cap 19, thus forming a container having a cubic content different from the cubic content of the container shown in Fig. 2. A still further arrangement of parts is shown in Fig. 1, wherein the two sleeves 12 are maintained in adjacent relationship to each other by means of the center sleeve 11. An additional sleeve 11 is readily secured to each end of the assembled sleeve 12, thus forming a container unit made up of two sleeves and three liners which container

may then be closed at each end by means of the caps 19.

In accordance with the foregoing description, it is apparent that the objects of the present invention have been achieved by providing a container insert comprising a liner having a spiral thread and a sleeve having a spiral thread receiving groove each adapted to be interconnected with each other and with additional liners and sleeves to form a container the cubic content of which depends upon the number of sleeves and liners used in constructing the container.

What I claim and desire to protect by Letters Patent is:

1. An adjustable container having a plurality of interconnected liner and sleeve elements, said liner and sleeve elements being tubular and of substantially the same length, a thread exteriorly of said liner elements and extending spirally throughout the length thereof, a thread receiving means disposed on the inner surface of said sleeve elements and extending spirally throughout the length thereof and adapted to receive said liner thread in locking relationship therewith, said sleeve elements and said liner elements being movable with respect to each other and being in abutting relationship with an adjacent liner element and sleeve element respectively, thereby providing a container having the sleeve elements and liner elements thereof adapted to vary the length of said container and positioned in a substantially continuous relationship with each other.

2. An adjustable container having a plurality of interconnected paper liner and paper sleeve elements, said liner and sleeve elements being tubular and of substantially the same length, a thread exteriorly of each of said liners and extending spirally throughout the length thereof, a thread receiving means disposed on the inner surface of each of said sleeve elements and extending spirally throughout the length thereof and adapted to receive said liner thread in locking relationship therewith, said sleeve elements and said liner elements being movable with respect to each other and being in abutting relationship with an adjacent liner element and sleeve element respectively, thereby providing a container having the sleeve elements and liner elements thereof adapted to vary the length of said container and positioned in a substantially continuous relationship with each other.

3. An adjustable container having a plurality of interconnected liner elements and sleeve elements, the liner elements and the sleeve elements being tubular and of substantially the same length, a thread exteriorly disposed on each of said liner elements and extending spirally throughout the length thereof, a thread interiorly disposed on each of said sleeve elements and extending spirally throughout the length thereof, the liner elements and the sleeve elements being movable in threaded relationship with each other and in abutting relationship to thereby lock the interconnected liner and sleeve elements, said liner and sleeve elements by addition or removal thereof, being adapted to adjust the length of said container, and closure means for each end of said container.

4. An adjustable container having a plurality of interconnected paper liner elements and paper sleeve elements, the liner elements and the sleeve elements being tubular and of substantially the same length, a thread exteriorly disposed on each of said liner elements and extending spirally

throughout the length thereof, a thread interiorly disposed on each of said sleeve elements and extending spirally throughout the length thereof, the liner elements and the sleeve elements being movable in threaded relationship with each other and in abutting relationship to thereby lock the interconnected liner and sleeve elements, said liner and sleeve elements by addition or removal thereof, being adapted to adjust the length of said container, and threaded closure means for each 10 end of said container.

5. An adjustable container having a plurality of interconnected paper liner elements and paper sleeve elements, the liner elements and the sleeve elements being tubular and of substantially the same length, a thread exteriorly disposed on each of said liner elements and extending spirally throughout the length thereof, a thread interiorly disposed on each of said sleeve elements and extending spirally throughout the length thereof, the liner elements and the sleeve elements being movable in threaded relationship with each other and in abutting relationship to thereby lock the interconnected liner and sleeve elements, said liner and sleeve elements by addition or removal thereof, being adapted to adjust the length of said container, and threaded closure means for each end of said container, said closure means being at each end of said container.
